HANGER FOR A TELEPHONE HANDSET

John W. Clearman, 181 N. Viceroy,
Azusa, Calif. 91702

Filed Jan. 3, 1967, Ser. No. 5,262

Term of patent 14 years

(Cl. D26—14)

FIG. 1

FIG. 3

FIG. 4

FIG. 5

FIG. 2

FIG. 6

FIG. 7

FIGURE 1 is a perspective view of a hanger for a telephone handset, showing my new design;

FIGURE 2 is a side view thereof;

FIGURE 3 is a bottom view thereof;

FIGURE 4 is a top view thereof;

FIGURE 5 is a front view thereof;

FIGURE 6 is a side view showing the side opposite the side shown in FIGURE 2; and

FIGURE 7 is a rear view thereof.

The broken lines representing the telephone handset are shown for illustrative purposes only.

I claim:

The ornamental design for a hanger for a telephone handset, as shown and described.
